UNITED STATES PATENT OFFICE.

ANTHONY JAMES HAILWOOD, OF BLACKLEY, MANCHESTER, ENGLAND, ASSIGNOR TO
BRITISH DYESTUFFS CORPORATION LIMITED, OF MANCHESTER, LANCASHIRE,
ENGLAND.

ELECTROLYTIC DESULPHONATION OF ANTHRAQUINONE SULPHONIC ACIDS.

Application filed December 8, 1926, Serial No. 153,473, and in Great Britain April 15, 1926.

The desulphonation of anthraquinone sulphonic acids has previously been carried out by heating solutions of the acids in 80 per cent sulphuric acid to high temperatures with the addition of mercury as a catalyst. I now find that by electrolytic reduction of the sodium or potassium salts of anthraquinone sulphonic acids in a divided cell, in alkaline solution, those acid groups occupying α -positions 5 are in great part removed and replaced by hydrogen, while those β -positions are scarcely affected. I find that under the reducing conditions of the cathode chamber reduction of the carbonyl groups of the anthraquinone residue readily takes place so that the product from which the α -sulphonic acid groups have been removed is found in the cathode solution as an oxanthrol. In alkaline solution a current of air suffices to oxidize 10 this to the anthraquinone in which form it is usually desired and separated. I find also from my work that under the conditions I use, the desulphonation is largely subsequent to reduction to the oxanthrol, and because in 15 the alkaline medium the oxanthrol is easily oxidized back to the quinone by air, it is necessary to exclude air or oxygen as much as possible from the cathode chamber in order to ensure efficient working. Many different 20 metals or alloys may be used as cathode; for example, mercury or amalgamated copper. The current density may be varied within wide limits, an advantageous current density being 2-3 amperes per square decimetre. The 25 quantity of electricity required is usually about 1.4 times that required by theory, due allowance being made for the two atoms of hydrogen required to reduce each molecule of anthraquinone to the corresponding oxanthrol. Although the process proceeds well at 30 ordinary temperatures, it is advantageous in most cases to carry out the operations at a higher temperature, particularly if the salts of the anthraquinone sulphonic acid or

oxanthrol sulphonic acid are sparingly soluble in the catholyte. The separation of the cathode and anode solutions may be achieved either by using a porous division of the pot type, or an impermeable division which dips into a mercury trap connecting the two solutions and which serves as cathode. 45

In the accompanying drawing, there is shown in longitudinal cross-section an apparatus for conducting the electrolysis. A receptacle or beaker 10 is provided with a 50 porous pot 11, in the bottom of which is placed a layer 12 of mercury serving as the cathode. Above the mercury is the catholyte 13, the composition of which is explained more fully below. The pot 11 is provided with an air-tight cover 14 through which passes a stirrer 15, an incased wire 16 leading to the mercury 12, and a vent tube 17 permitting the escape 55 of gases generated during the electrolysis. It will, of course, be understood that the essential elements contained within the porous pot 11, and forming a portion of the entire apparatus, constitute the cathode chamber. Surrounding the cathode chamber is the anolyte 18 of sodium hydroxid solution, into 60 which extend anodes 19. 65

The following examples are intended to illustrate the nature of my invention but I do not limit myself to the particular details thereof:— 70

Example 1.—25 grams disodium anthraquinone-1:5-disulphonate are dissolved in 1 litre of hot water containing 14 grams of sodium hydrate solution. The solution so obtained is introduced into a cathode chamber, which consists of a porous pot on the bottom of which is a layer of mercury serving as the cathode. The porous pot is fitted with an air-tight lid through which passes a stirrer, a cathode lead and a tube to carry off excess 75 hydrogen. The cathode chamber is surrounded by a 25 per cent aqueous solution of sodium hydrate which acts as the anolyte. 80 85

The anode is some suitable conductor such as carbon or an iron plate. A current at a density of 2-3 amperes per square decimetre is then calculated on the cathode surface is then 5 passed until about 13-17 ampere-hours have

passed through the cell. The catholyte is then removed and a current of air blown through it until the red-colour due to the oxanthrol is discharged.

The reaction is as follows:

10

The anthraquinone is filtered off, washed with water and dried. It is already very pure and may be obtained quite pure by a single sublimation or recrystallization for example from toluene. The yield of anthraquinone is about 70 per cent calculated on the disulphonic acid used. In addition, there is an appreciable quantity of mono-sulphonic acid left in the solution.

20 *Example 2.*—11 grams of the dipotassium salt of anthraquinone-1:8-disulphonic acid, 6 grams potassium chloride and 300 grams of water forms the catholyte and a 10 per cent aqueous solution of potassium carbonate forms the anolyte. The cell-arrangement is the same as in Example 1, a mercury cathode being used. The temperature conditions are the same as before and 6 ampere-hours of electricity at a current density of 2 amperes per square decimetre are passed. The product is worked up as in Example 1.

25 *Example 3.*—300 cc. of a 2.2 per cent solution of the disodium salts of 1:6- and 1:7-disulphonic acids of anthraquinone containing small quantities of the sodium salts of the

1:5- and 1:8- disulphonic acids obtained as a waste product, are treated with 4.2 grams of sodium hydrate and subjected to electrolytic reduction in the cathode chamber of the cell described in Example 1 under the same 40 conditions. After 3.5 ampere-hours of electricity are used, the brownish-red solution is oxidized with a current of air and filtered from a small quantity of anthraquinone. The filtrate containing a large proportion of β -mono sulphonic acid may be worked up for this, by the following process, for example. The solution is acidified with hydrochloric acid and the sulphur dioxide boiled off and to the hot solution an aqueous solution of β -naphthylamine hydrochloride in excess is added. The β -naphthylamine-anthraquinone- β -sulphonate which crystallizes out is filtered off and decomposed with sodium hydrate solution to give β -naphthylamine and 45 sodium anthraquinone- β -sulphonate which 50 are easily separated by their different solubilities in water.

55 The reaction is as follows:

60 *Example 4.*—5 grams of the sodium salt of anthraquinone- α -sulphonic acid are dissolved in 300 cc. water containing 4.2 grams of sodium hydrate in solution and the product

is subjected to electrolysis, as in Example 1, 2½ ampere-hours of electricity being used. The product is oxidized by air as before described. The anthraquinone produced is 5 filtered off, washed with water, and dried. The yield is 66 per cent of theory.

What I claim and desire to secure by Letters Patent is:—

1. A process for the manufacture of ox- 10 anthrol derivatives from anthraquinone compounds containing α -sulphonic acid groups, consisting in the reduction of, and the removal of such α -sulphonic acid groups from, such anthraquinone compounds by electrolytic reduction in alkaline solution.

2. A process for the manufacture of an- 15 thraquinone and anthraquinone compounds derivatives from compounds containing α -sulphonic acid groups thereof, consisting in the reduction of, and the removal of such α -sulphonic acid groups from, such anthra- 20 quinone by electrolytic reduction in alkaline solution to produce oxanthrol derivatives, fol-

lowed by oxidation of the resulting oxanthrol derivatives.

3. A process for the manufacture of par- 25 tially desulphonated oxanthrol poly-sulphonic acids from compounds containing anthraquinone α -sulphonic acid groups consisting in the reduction of, and the removal of one or more such α -sulphonic acid groups from, such compositions by electrolytic reduction in alkaline solution.

4. A process for the manufacture of par- 30 tially desulphonated anthraquinone polysulphonic acids from compositions containing α -sulphonic acid groups thereof consisting in the reduction of, and the removal of one or more α -sulphonic acid groups from, such compositions by electrolytic reduction in alkaline 35 solution to produce oxanthrol derivatives, followed by oxidation of the resulting oxanthrol derivatives, substantially as described.

In testimony whereof I affix my signature.
ANTHONY JAMES HAILWOOD.
